United States Patent Office.

D. R. GOULD, OF CHESTERTOWN, NEW YORK.

Letters Patent No. 64,307, dated April 30, 1867.

IMPROVEMENT IN HYDRANTS.

The Schedule referred to in these Letters Patent and making part of the same.

TO ALL WHOM IT MAY CONCERN:

Be it known that I, D. R. GOULD, of Chestertown, in the county of Warren, and in the State of New York, have invented, new and useful improvements in Hydrants; and do hereby declare that the following is a full, clear, and exact description thereof, reference being had to the accompanying drawings, and to the letters of reference marked thereon. In the annexed drawings, making part of this specification—

A represents the box which covers or contains the hydrant. Near the bottom of this box A is situated a metallic case, B, which is provided with a top, B'. When the top B' is secured upon the case there is a chamber within the vessel thus formed, similar to the shape of the two cones with their bases joined together. Within the chamber of case B is situated a valve, F, the shape of which is made similar to that of the chamber, but somewhat smaller, so as to be allowed play. E represents a rod or stem, which passes through the cover B', the valve F, and through the case B at its bottom. The opening through which the stem passes in the bottom of the case is made larger than the diameter of the stem, so as to allow of the escape of water around said stem when necessary. C represents a pipe which connects with the case B on one side, and D a pipe which connects with it on the other; C representing the supply and D the discharge pipe. In one side of the valve F is formed a groove, α , which, when the valve is closed, opens a communication from the discharge pipe D to the opening around the stem E in the bottom of case B to allow of the escape of waste water. β represents a plate on stem E, beneath the case B, which is supported upon a coiled-wire spring, α , which is for the purpose of closing the waste-opening in the bottom of the case when the valve is raised. The upper end of the rod E has its bearing in an arm, K, on a plate, J, which said plate is secured to the box covering the hydrant. L represents a lug upon the stem E, and G a spring which is confined around the stem between the arm K and said lug L. The spring is for the purpose of pressing the stem with its valve down firmly in the case B. H represents a lever, one end of which catches under the lug L, and the other end of which is operated upon by means of a cam-handle, I. The valve F is raised and lowered by means of the stem E. When said valve is down it shuts off the water from the supply pipe C, and the waste water from pipe D runs down through groove α and out, around the stem E, through the opening in the bottom of the case B. When the valve F is up this water from pipe C passes through case B and up through discharge pipe D. The handle I operates upon the lever H, and said lever operates the rod or stem E in one direction, while the spring G operates it in the other; one opens and the other closes the valve.

Having thus fully described my invention, what I claim as new, and desire to secure by Letters Patent, is—

1. The valve F, constructed as described, and provided with the groove α , and arranged in connection with the case B and the discharge pipe D, substantially as and for the purpose specified.

2. The arrangement of the plate β , supported upon the spring α , and used in combination with the opening in the bottom of the case B and the stem E, substantially as and for the purpose specified.

In testimony that I claim the foregoing I have hereunto set my hand and seal this 8th day of February, 1867.

D. R. GOULD.
